(22) Filed: **Apr. 28, 2006**

The ornamental design for an exhaust pipe for a vehicle, as shown and described.

(30) **Foreign Application Priority Data**

DESCRIPTION

Oct. 31, 2005 (EM) 000424528-0001

This application is related to the following co-pending applications, of the inventor, filed on even date herewith: Application Ser. No. 29/258,853, entitled "Surface Configuration Of A Vehicle, Toy, and/or Other Replicas"; and Application Ser. No. 29/258,843, entitled "Surface Configuration of a Vehicle, Toy, and/or Other Replicas".

(51) **LOC (8) Cl.** **12-16**

FIG. 1 is a perspective view of a first embodiment of an exhaust pipe for a vehicle according to my novel design; and FIG. 2 is a front elevation view thereof.

(52) **U.S. Cl.** **D12/194**

FIG. 3 is a perspective view of a second embodiment of the exhaust pipe for a vehicle according to my novel design; and,

(58) **Field of Classification Search** D12/194;

FIG. 4 is a front elevation view thereof.

293/113; 181/227, 228, 247-249, 264, 282,

The broken lines are for illustrative purposes only and form no part of the claimed design.

181/239-241; D15/5; 138/37-39, 44, 103,

138/109

See application file for complete search history.
